UNITED STATES PATENT OFFICE.

WILLARD F. RICHARDS, OF BUFFALO, NEW YORK, ASSIGNOR TO THE GOULD COUPLER COMPANY, OF NEW YORK, N. Y.

DESIGN FOR A SIDE FRAME FOR CAR-TRUCKS.

SPECIFICATION forming part of Design No. 26,585, dated February 2, 1897.

Application filed December 29, 1896. Serial No. 617,410. Term of patent 14 years.

To all whom it may concern:

Be it known that I, WILLARD F. RICHARDS, a citizen of the United States, residing at Buffalo, in the county of Erie and State of New York, have invented and produced a new and original Design for Side Frames for Car-Trucks, of which the following is a specification, reference being had to the accompanying drawings, forming a part thereof.

10 This design relates to the shape or configuration of the side frame of a car-truck, more particularly of a truck for freight-cars.

In the accompanying drawings, Figure 1 is an elevation of the outer or front side of a side frame embodying my design. Fig. 2 is an elevation of the inner or rear side thereof. Fig. 3 is a top plan view of the same. Fig. 4 is a vertical cross-section in line 4 4, Fig. 1. Fig. 5 is a vertical cross-section in line 5 5, Fig. 1.

Like letters of reference refer to like parts in the several figures.

The leading feature of my design consists of a rectangular panel arranged in the middle of the side frame, circular horizontal enlargements arranged at the ends of the frame, a pair of outwardly-converging bars arranged on each side of said panel and extending from the upper and lower corners of the panel to said enlargement, and upright bars extending downwardly from the outer meeting ends of said converging bars.

Referring to the drawings, A is the rectangular central panel, having on its outer side a rectangular flange *a*, having its sides ar-

ranged parallel with the edges of the panel, and on its rear side a deep rectangular flange or box *A'*, as shown in Fig. 2.

B are the circular horizontal enlargements arranged at the ends of the side frame and 40 having outwardly-projecting ears *b*.

C represents upper inclined bars which extend from the upper corners of the central panel to the enlargements B, and D lower reversely-inclined bars extending from the 45 lower corners of said panel to said enlargements and connected at their inner ends by a horizontal bar D', arranged below the central panel and forming with said lower bars an inverted arch. The inclined bars CD have 50 marginal flanges *e* at both of their edges and on opposite sides thereof, as shown in Figs. 1 and 4. The flanges on the inner side of the bars C gradually widen toward the deep flange or box *A'*, as shown in Fig. 3.

55 *f* are longitudinal ribs or flanges arranged centrally on the upper side of the upper bars C and increasing in width toward the enlargements B.

G are upright bars extending downwardly 60 from the outer ends of the converging bars CD.

What I claim is—

The design for the side frame of a car-truck, substantially as herein shown and described.

Witness my hand this 26th day of December, 1896.

WILLARD F. RICHARDS.
